UNITED STATES PATENT OFFICE

ALBERT C. PREISIG, OF SAN FRANCISCO, CALIFORNIA, ASSIGNOR TO KEYSTON BROS.,
OF SAN FRANCISCO, CALIFORNIA, A CORPORATION OF CALIFORNIA

DESIGN FOR A BOY'S PISTOL HOLSTER

Application filed November 24, 1931. Serial No. 41,849. Term of patent 7 years.

To all whom it may concern:

Be it known that I, ALBERT C. PREISIG, a citizen of Switzerland, residing at the city and county of San Francisco, State of California, have invented a new, original, and ornamental Design for a Boy's Pistol Holster, of which the following is a specification.

Referring to the accompanying drawings:
Fig. 1 is a front elevation of the holster, showing my new design. Figure 2 is a side elevation thereof.

I claim:

The ornamental design for a boy's pistol holster substantially as shown.

In testimony whereof I have signed my name to this specification.

ALBERT C. PREISIG.
